UNITED STATES PATENT OFFICE.

H. ERICK ERICKSON, OF GRANDY, MINNESOTA.

JAR-HOLDER.

1,162,045.

Specification of Letters Patent.

Patented Nov. 30, 1915.

Application filed February 24, 1915. Serial No. 10,344.

To all whom it may concern:

Be it known that I, H. ERICK ERICKSON, a citizen of the United States, residing at Grandy, in the county of Isanti, State of Minnesota, have invented certain new and useful Improvements in Jar-Holders; and I do hereby declare the following to be a full, clear, and exact description of the invention, such as will enable others skilled in the art 10 to which it appertains to make and use the same.

This invention relates to a jar holder particularly to the class of jar holders which are adapted to be used for supporting jars 15 in boiling water during the insertion of fruit into the same during a canning operation.

An object of the invention resides in the provision of a device of this character which 20 is so constructed as to be readily applicable to a canning boiler, as well as all kinds of water boilers.

A further object of the invention resides in the provision for the adjustment of the 25 device so that it may be used in connection with boilers of various depths.

A further object of the invention resides in so constructing the device that the jars carried thereby will be supported out of 30 contact with the bottom of the boiler.

With these and other objects in view, such as will appear as the description progresses, my invention comprises the combination and arrangement of parts as set forth in and 35 falling within the scope of the appended claims.

Referring to the drawing: Figure 1 is a side elevation of my device, showing the same applied to a boiler. Fig. 2 is a plan view thereof. Fig. 3 is an end elevation. Fig. 4 is a detail of the means for supporting the device on a boiler.

Referring to the drawing wherein like parts are indicated by like characters throughout the several views: My device comprises a main body portion 1 which is made of wood, metal or any other suitable material. Pivoted mounted on each end of the body portion 1 is a holder by means of 45 which the body portion may be supported from a boiler, as shown in Fig. 1. Each of these holders 2 consists of a substantially rectangular portion 3 which is pivoted to the body portion 1 at one of the lower corners of the rectangle. These holders are so arranged that they extend outwardly from

the body portion from opposite sides thereof. Secured to the lower horizontal portion 4 of each of these holders 2 is a guide member 5 through which is slidably mounted a strip 6 having a hook-shaped portion 7 on the upper end thereof constructed and arranged to engage the upper edge of a boiler. In order that these strips may be maintained in predetermined fixed relation with the 65 rectangular portions 3, I have provided each with a longitudinally extending slot 8 through which extends a bolt 9 secured to the upper horizontal bar 10 of the said rectangular portion and having a nut 11 adjustably secured to the end thereof which may be screwed onto the said bolt so as to bind the strip between it and the horizontal bar 10.

In order that the hooks 7 may be secured 75 to the upper edge of the boiler, I have provided thumb screws 12 which extend through the hooks and are arranged to engage the outer face of the boiler. Secured to and extending outwardly from each side 80 of the body portion 1 adjacent the bottom thereof are arms 13 which are constructed so as to engage the sides of the boiler and thus prevent the body portion 1 from swinging out of the vertical when a number of 85 jars are supported on one side thereof.

In order that the jars may be supported on the body portion 1, I have provided a plurality of loops 14 secured to the body portion 1 and extending outwardly above 90 the upper edge thereof and from both faces thereof. These loops are constructed to encircle the upper ends of the jars. These loops 14 terminate in downwardly extending arms 14' which are secured to the faces 95 of the body portion 1 by means of suitable fasteners 14'', the arrangement being clearly shown in Figs. 1 and 3. In order that the bottom of the jars may be supported and the jars thus held on the body portion, I 100 have provided a plurality of spring bases 15 which are mounted on a rod 16 extending longitudinally of the body portion 1.

When it is desired to use the device the strips 6 are adjusted to their proper positions so as to accommodate the device to the particular boiler and the device lowered within the boiler until the hooks 7 engage the upper edge thereof, at which time the thumb screws 12 are screwed inwardly to 110 bind the strips 6 on the said boiler, the jars are then placed through the loops 14 and

rest on the bases 15 so that the upper ends thereof will extend slightly out of the boiling water within the boiler. The fruit is then poured into the jars in the usual manner.

From the foregoing description it will be seen that I have provided a jar holder for supporting a plurality of jars during the filling of the same in canning fruit, I have so constructed the device that it may be adjusted to be used on various sized boilers, and I have provided means for preventing the swinging of the device when the jars are supported only on one side thereof.

While I have illustrated and described a particular embodiment of my invention, I have merely done so for the sake of convenience and I do not wish to be limited to that particular embodiment as it is obvious that numerous changes may be made within the details of construction thereof without in any way departing from the spirit of the invention or exceeding the scope of the appended claims.

What I claim is:—

1. In a jar supporting device, a body portion, supporting members pivotally mounted

on each end thereof consisting of rectangular members, hook-shaped strips adjustably secured thereto for engaging the top edge of a boiler, means secured to and extending outwardly from each side of the body portion for supporting jars, and means for preventing the lateral movement of the body portion.

2. In a jar holding device constructed and arranged to be suspended from the upper edge of a boiler and locked within the same, and means for adjustably securing the body portion to the upper edge of the boiler, arms extending outwardly from each face of the body portion, loops secured to and extending outwardly from the opposite faces of the body portion adjacent the upper edge thereof, and spring pressed bases located beneath said loops arranged to engage and support the bottom of jars in spaced relation to the bottom of the boiler.

In testimony whereof, I affix my signature, in the presence of two witnesses.

H. ERICK ERICKSON.
